United States Patent Office

Des. 233,838
Patented Dec. 3, 1974

233,838

ROOM AIR CONDITIONER OUTER CASE OR SIMILAR ARTICLE

Walter Baker, Jr., Louisville, Ky., assignor to
General Electric Company

Filed July 30, 1973, Ser. No. 383,812

Term of patent 14 years

Int. Cl. D23—04

U.S. Cl. D23—141

FIG. 1

FIG. 3

FIG. 2

FIG. 1 is a perspective view of a room air conditioner outer case or similar article showing my new design.

FIG. 2 is a left side elevational view thereof, the right side being identical.

FIG. 3 is a rear elevational view thereof.

I claim:

The ornamental design for a room air conditioner outer case or similar article, as shown and described.
